UNITED STATES PATENT OFFICE.

GEORGE W. PECK, OF SAN LUIS OBISPO, CALIFORNIA.

COMBINED BLACKING-BRUSH AND BLACKING-BOX.

SPECIFICATION forming part of Letters Patent No. 374,696, dated December 13, 1887.

Application filed November 11, 1886. Serial No. 218,657. (No model.)

To all whom it may concern:

Be it known that I, GEORGE W. PECK, of San Luis Obispo, San Luis Obispo county, State of California, have invented an Improvement in Combined Blacking-Brush and Blacking-Box; and I hereby declare the following to be a full, clear, and exact description of the same.

My invention relates to a new and useful combined brush and box for blacking purposes; and my invention consists in a brush the frame or stock of which on its back is provided with a spring-metal plate, forming a clamp, and a box fitting upon the back of said stock or frame, under the plate or clamp, whereby it is secured in place, said box having no other cover or lid than that furnished by said plate or clamp, as I shall hereinafter fully describe.

The object of my invention is to provide a blacking-brush and blacking-box intimately united or connected, so that the two may be always found together and be ready for immediate and convenient use.

Referring to the accompanying drawings for a more complete explanation of my invention, Figure 1 is a perspective view of my combined blacking-brush and blacking-box. Fig. 2 is a plan view of the same, showing the blacking-box partially pulled out from its seat, in order to show the absence of its cover or lid.

A is the blacking-brush, of any suitable pattern, though I prefer the style here shown. On the back of the frame or stock *a* of the brush is firmly secured a plate, B, which is made of spring metal, so that it may form a clamp. The plate B is approximately of the contour and area of the back portion of the frame or stock of the brush over which it extends, being separated therefrom by a space sufficient for the reception of the blacking-box.

C is the blacking-box, which, though it may have a cover or lid, as usual, is preferably formed without one, so that when said box is removed completely from its connection with the brush its contents shall be immediately and fully exposed. The box fits upon the back of the stock or frame of the brush, under the plate B, which, being of a springy character, clamps said box firmly to its seat, and acts at the same time as a cover or lid for said box. In use, the box is first removed from its plate, so that its contents may be reached by the rubber portion of the brush. When the operation is finished, the box is placed back in its seat, and there remains intimately connected with the brush, so that there is no danger of misplacement, the two being always found together, and saving all loss of time in searching for one or the other. Another advantage of this construction is that the box is always covered, and thereby much of its contents is saved from waste. On account of the compact construction, the device will be found useful for travelers.

A handle, D, may be provided.

Having thus described my invention, what I claim as new, and desire to secure by Letters Patent, is—

In combination with the blacking-brush A, having a frame or stock, *a*, the spring plate or clamp B on the back of said frame or stock, and the coverless blacking-box C, fitting on the back of the frame or stock, under the plate or clamp, which holds it to its place and forms a cover for it, substantially as herein described.

In witness whereof I have hereunto set my hand.

GEORGE W. PECK.
